UNITED STATES PATENT OFFICE

107,408

DESIGN FOR A FISH LURE

Sam F. Davenport, Garrett, Ind., assignor to Creek Chub Bait Company, Garrett, Ind.

Application June 5, 1937, Serial No. 69,703

Term of patent 14 years

To all whom it may concern:

Be it known that I, Sam F. Davenport, a citizen of the United States, residing at Garrett, in the county of De Kalb and State of Indiana, have invented a new, original, and ornamental Design for a Fish Lure, of which the following is a specification, reference being had to the accompanying drawing, forming part thereof.

I claim:

The ornamental design for a fish lure as shown.

SAM F. DAVENPORT.
